(57) **CLAIM**

I claim the ornamental design for a remote control, as shown and described.

DESCRIPTION

FIG. 1 is a top, front, left side perspective view of my new design of a remote control.

FIG. 2 is a top, rear, right side perspective view thereof.

FIG. 3 is a front side elevational view thereof.

FIG. 4 is a rear side elevational view thereof.

FIG. 5 is a top plan view thereof.

FIG. 6 is a bottom plan view thereof; and,

FIG. 7 is a right side elevational view thereof, the left side elevational view being a mirror image thereof.
